UNITED STATES PATENT OFFICE.

WALTER H. WHITTIER, OF GRAND RAPIDS, MICHIGAN, ASSIGNOR TO GRAND RAPIDS
REFRIGERATOR COMPANY, OF GRAND RAPIDS, MICHIGAN, A CORPORATION OF
MICHIGAN.

LATCH.

1,140,553.

Specification of Letters Patent. Patented May 25, 1915.

Application filed April 13, 1914. Serial No. 831,529.

To all whom it may concern:

Be it known that I, WALTER H. WHITTIER, a citizen of the United States of America, residing at Grand Rapids, in the county of Kent and State of Michigan, have invented certain new and useful Improvements in Latches; and I do hereby declare the following to be a full, clear, and exact description of the invention, such as will enable others skilled in the art to which it appertains to make and use the same.

This invention relates to improvements in latches, and more particularly to door latches for refrigerator doors and the like, and its object is to provide a latch which when engaged will exert a constant tension to maintain the door tightly closed; which may be easily latched and unlatched; which will be simple in construction and operation, and to provide the device with various new and useful features hereinafter more fully described and particularly pointed out in the claims, reference being had to the accompanying drawings, in which:—

25 Figure 1 is a section of a portion of a door and casing, with the improved latch applied thereto, said section being taken on the line 1—1 of Fig. 2; Fig. 2 is a transverse section on the line 2—2 of Fig. 1, showing 30 the latch engaged; and Fig. 3 shows the same parts as Fig. 2, and illustrates the method of disengaging the latch.

Like numbers refer to like parts in all of the figures.

35 1 represents a hinged door and 2 a door casing.

3 is a rigid arm projecting from a base 4 attached to the door. The arm 3 is adapted to engage retaining rollers 6 mounted on the 40 respective ends of a spring 5, which spring is fastened to the casing 2, the said spring serving to yieldably force the rollers 6 toward each other. The arm 3 is provided with oppositely inclined inner surfaces 45 which meet in an acute angle at the inner edge and with inclined outer surfaces which meet in an obtuse angle at the outer edge forming opposing wedge portions successively engaged by the rollers.

50 A lever 7 is pivoted in the bifurcated extension 8 of the base 4 and is provided with a stop shoulder 7^a which engages the said base to limit the movement of the lever toward the door. The lever extends over 55 the arm 3 and is there provided with a re-

leasing portion 9 having oppositely inclined surfaces adapted to engage the rollers 6 and separate them to release the arm.

A housing 10 surrounds the spring 5 and retaining rollers 6 and is provided with an opening 11 to admit the arm 3 and the releasing portion 9 of the lever 7.

In operating this latch, when the door is being closed its momentum will cause the acute angled wedge shaped side of the arm 65 3 to pass between the retaining rollers 6 forcing the same apart, and the rollers will engage the obtuse angled inclined outer surfaces of said arm, and owing to the tendency of the spring 5 to force the rollers toward 70 each other they will exert a constant inward pressure on the outer obtuse wedge of said arm to force the door to tightly closed position. To disengage the latch the lever 7 is pulled outward, which moves the releasing 75 portion 9 toward the arm 3 and its inner oppositely inclined surfaces will separate the rollers 6, releasing the arm, disengaging the latch and at the same time operating as a lever to force the door open by pressure 80 against the rollers.

It is obvious that this device is desirable, both from the standpoint of efficiency, simplicity of operation and cheapness of construction.

85 What I claim is:—

1. A latch, comprising an arm adapted to be attached to a door and having oppositely inclined inner and outer surfaces retaining members yieldably forced toward 90 each other and adapted to be attached to a door casing and a lever opposite the arm having oppositely inclined surfaces to engage and separate the retaining members.

2. A latch, comprising a rigid arm adapted to be attached to a door retaining members yieldably forced toward each other, means for attaching the same to a door casing, and a pivoted lever opposite the arm having oppositely inclined inner surfaces to 100 separate said retaining members and release the arm.

3. A latch, comprising an arm, means for rigidly attaching the same to a door, said arm having inclined inner and outer oppositely inclined surfaces, retaining members yieldably forced toward each other, means for attaching the same to a door casing, said members being separated by the inner inclined surfaces of the arm and engaging 105 110

the outer surfaces of the same, and a pivoted lever extending parallel with the arm and having oppositely inclined inner surfaces; for engaging and separating said members to release the arm.

4. A latch, comprising an arm rigidly attached to a door and having oppositely inclined inner and outer surfaces, retaining members yieldably forced toward each other and attached to a door casing, said members being separated by the inner inclined surfaces of the arm and engaging the outer surfaces thereof, and a lever pivotally attached to the door and having one end serving as a handle for manually opening and closing the door and the other end having oppositely inclined surfaces to engage and separate said retaining members.

5. A door latch, comprising a base adapted to be attached to a door, an arm projecting therefrom, said arm having oppositely inclined inner and outer surfaces, retaining rollers journaled on the respective ends of a spring adapted to be attached to a casing and yieldably moving the rollers toward each other, said rollers being separated by

the inner inclined surfaces of the arm and engaging the outer inclined surfaces thereof, and a lever pivoted intermediate its ends to said base, one of its ends serving as a handle for a door and the other end having a releasing portion with oppositely inclined surfaces by which the said rollers may be separated to release the arm.

6. A door latch comprising a rigid arm having an acute inner angle and opposing inclined inner surfaces, an obtuse outer angle and opposed inclined outer surfaces, a pivoted lever having one end serving as a handle and the other end extending parallel with said arm and provided with an inner angle opposite the arm and oppositely inclined inner surfaces, and a spring carrying rollers oppositely engaging all of said inclined surfaces in succession.

In testimony whereof I affix my signature in presence of two witnesses.

WALTER H. WHITTIER.
